LAMP SHADE RETAINER

Souren R. Kazanjian, New York, N. Y.

Application January 17, 1942, Serial No. 427,108

3 Claims. (Cl. 240—129)

This invention relates to lamp shade retainers.

The invention may have application in many different relations. It will be described specifically in connection with an assembly wherein a lamp shade is to be retained in association with an electric-light-bulb-retaining socket. Among the many different forms of devices utilized to retain glass or metallic lamp shades in association with different types of bulb-retaining sockets are those which use set-screws to engage shade or socket, as the case may be. The manipulation of these screws may result in breakage of the shade, for instance, where the flange of a glass shade is engaged by such set-screws. In any case the manipulations necessary to position the usual shades may become awkward.

It is an object of the invention to provide a simple construction by which an adjustable clamping mechanism provides means for retaining a shade in association with a socket. In such construction, substantially all the elements of the retaining device may be housed within an annular member, such as usually forms a flange for a socket or shade retaining member. The actuating portions, that is, the portions which are actually manipulated by a person in setting up the assembly, may be constituted by one or more small projections.

It is an object of the invention to provide a construction for retaining a lamp shade in association with a bulb-retaining socket or similar element, wherein a simple encircling band makes substantially continuous contact with a portion of shade or socket, as the case may be, positively to locate and retain the shade in position in relation to the socket.

Other objects of this invention will be set forth hereinafter, or will be apparent from the description and the drawings in which are illustrated embodiments of apparatus exemplifying the invention.

The invention, however, is not intended to be restricted to any particular construction, or any particular arrangement of parts, or any particular application of any such construction or arrangement of parts, or any specific method of operation or use, or any of various details thereof, even where specifically shown and described herein, as the same may be modified in various particulars or may be applied in many varied relations without departing from the spirit and scope of the claimed invention, of which the exemplifying embodiments, herein shown and described, are intended only to be illustrative, and only for the purpose of complying with the re-

quirements of the statutes for disclosure of an operative embodiment, but not to show all the various forms and modifications in which the invention might be embodied.

5 On the drawings, in which the same reference characters refer to the same parts throughout, and in which the exemplifying embodiments appear:

Fig. 1 is an elevational view, the lampshade 10 and the device embodying the invention being broken away in section to illustrate the manner in which certain features of the invention are applied;

15 Fig. 2 is a cross-sectional view, substantially on the line 2—2 of Fig. 1;

Fig. 3 is an elevational view of the detail embodying features of the invention, parts being broken away in section to clarify the construction;

20 Fig. 4 is an elevational view of the band utilized in the invention, the band being stretched out flat;

Fig. 5 is a detail cross-sectional view, substantially on the line 5—5 of Fig. 2;

25 Fig. 6 is an elevational view, illustrating the manner of application of the invention in connection with an electric light bulb socket and a lampshade;

Fig. 7 is a cross-sectional view, substantially on the line 7—7 of Fig. 6;

30 Fig. 8 is a detail cross-sectional view, substantially on the line 8—8 of Fig. 7, to illustrate the arrangement of the guard;

Fig. 9 is a detail in cross-section of a portion 35 of the shade shown assembled with the device in Fig. 6;

Fig. 10 is a cross-sectional view, similar to Fig. 2, but to enlarged scale, and showing the band and its manipulating parts, other parts being shown in dot-and-dash lines, to illustrate the manner in which the band is positioned when distended; and

Fig. 11 is a view, similar to Fig. 10, illustrating the position the band assumes when manipulated to clasp the socket in Fig. 1.

In the construction shown on Figs. 1 to 5, inclusive, an ordinary bulb-retaining socket 10 is shown. Such socket may be supported in any desired manner. In the structure illustrated, it is suspended from a cable or similar electrical conductor 12, which in turn may be suspended from the ceiling or the like. Socket 10 itself may, if desired, be provided with any suitable circuit-making means 14, as, for instance, a switch. The socket may have the usual recess 16, with means

such as the usual threaded contact sleeve 18 for retaining a bulb 20 in position. Socket 10 may be made of any desired material; porcelain or similar material is useful in this connection. In wall 22 of the socket, and immediately above the bottom opening 24 of recess 16 in which contact 18 is seated, may be a groove 26. Such a groove may be found substantially on all such sockets. Shade 28 is intended to be associated with a member such as socket 10. The shade may be of any suitable construction; it is here shown as of metallic construction; also, it may be of any suitable contouring, as, for instance, substantially conical. At the peak, the cone is cut off to provide an opening 30 at which an annular member or ring 32 is assembled. Ring 32 may be secured to shade 28 at opening 30 in any desired manner. For instance, ring 32 may include a cylindrical strip 34 extending down from an inturned flange 36 of the ring. Strip 34, in turn, may be beaded into opening 30, and into contact with the rounded edge 38 at the inner face 40 of shade 28 at the opening. Bead 42 may then be secured to face 40, as, for instance, by soldering or otherwise, to integrate ring 32 with rounded edge 38.

Ring 32 may be spun or otherwise formed to provide a substantial recess 44 defined between a wall 46 and a pair of inturned flanges 36 and 48, respectively, at bottom and top of wall 46. These flanges extend inwardly, and may be turned to define lips 50 and 52. Thus, recess 44 forms means to receive a band 54, the construction of which will be discussed further and more fully. Extending across recess 44 and between lips 50 and 52 may be a plurality of spaced straps 56. These straps serve to retain band 54 against separation from ring 32, and also serve to impart a definite arcuate contour to band 54.

It will be noted from Figs. 2, 4, 10 and 11, that band 54, which may be made of spring metal bent into the arcuate form shown, extends more than 360°, and, in fact, extends almost 720°. Substantially the entire band is housed within the extent of recess 44. The band is narrow in its vertical extent. Band 54 is reduced in its transverse extent to form a slip section 58. At section 60, an elongated slot 62 is formed in band 54, and is of sufficient width so that slip section 58 may move therethrough.

One end 64 of band 54 may be anchored to ring 32 in any desired manner, as, for instance, by being riveted or soldered thereto. For the other end 66 of the band a handle or manipulating member 68 may be provided. To retain the handle in position a suitable construction may include an opening 70 formed through band 54 and receiving an end 72 of handle 68. This end 72 may be headed over to lock end 66 with relation to handle 68.

In addition to headed over end 72, handle 68 may have a short stem 74 of such dimensions that it may extend through a slot 76 in wall 46. Beyond stem 74, handle 68 has an enlarged grip 78 to be grasped by one's fingers. An ear 80 may be affixed to the outside face of wall 46. The extent of slot 76 is such that handle 68 may be brought to an end 82 of the slot, adjacent to which ear 80 may be located. Ear 80 may be a handle similar to handle 68, and, in the same manner as handle 68, may be secured to end 64, and extend through slot 76. Thus, it would be possible to bring both handle 68 and ear 80 into association with each other. To prevent rota-

tion of shade 28 with relation to socket 10 during such manipulation, the form shown on the drawings, in which end 64 is anchored directly to wall 46 at its inner face, has been found desirable.

As handle 68 is manipulated to approach ear 80, ends 64 and 66 of the band 54 approach each other, and consequently reduce the area encompassed by the inner faces of the band. This is made even more effective where straps 56 control band 54. If socket 10 be positioned so that its groove 26 is in immediate proximity to band 54, the band, on such movement of handle 68 towards ear 80, will become seated in groove 26, and lock shade 28 and socket 10 together.

In order to retain the members in this associated relationship, ear 80 may be locked in fixed relation to handle 68 by any suitable means. For instance, ear 80 may have an opening 84 which may include a substantially spherical recess 86. Recess 86 may form a bearing for a ball-shaped bearing portion 88 provided upon a stem 90 of a screw 92. Recess 86 and portion 88 cooperate to retain screw 92 against longitudinal movement, and yet permit limited rotation of the stem about its longitudinal axis and also limited swinging movement of the stem into a number of different positions, portion 88 then acting as a bearing.

Grip 78 may have a socket 93 in which is seated a ball member 95 having a screw-threaded passage 94 formed therethrough. The threaded portions of screw 92, when stem 90 is properly swung into position, after grip 78 has been brought adjacent to ear 80, may be engaged in passage 94. Then, by turning manipulating head 98 of screw 92, handle 68 may be cammed into closer relation to ear 80, and the gripping action of band 54 in groove 26 may be increased. Thus, socket and shade may be fixedly anchored to each other, or, by unthreading screw 92 from passage 94, handle 68 may be moved away from ear 80, and the shade then separated from the socket. When handle 68 and ear 80 are thus separated, screw 92 will still be retained against loss by reason of the cooperation of portion 88 with recess 86, and will remain in position for immediate engagement in passage 94 when grip 78 is approached properly to ear 80.

In Figs. 6 to 9, inclusive, a modified construction is shown in which a shade 100 is carried from a ring 102, where ring 102 may have a threaded flange 104 to be engaged upon the complementary threaded portions 106 of a metallic electric light socket 108 of usual construction. The purpose of such construction is to suspend a glass or similar shade with relation to socket 108. In this case, ring 102 has a wall 110 which connects flange 104 to an annular wall 112. Wall 112, like ring 32, is, by means of a flange 114 and turned-in prongs 116, formed so as to provide a recess 118 for receiving a band 120.

Band 120, like band 54, may have a reduced portion 122 for passage through a slot 124 formed in band 120. One end 126 of the band may be anchored to wall 112. The other end 130 of the band may be passed through an angularly and tangentially cut slot 132 formed in wall 112 so as to appear at the outer face 134 of wall 112. At this outer face, a guard 136, shaped to conform to the contouring of wall 112, may be secured to end 130. This guard is formed by an arcuate plate having bent back flanges 137 at its edges for engagement over the edges of an arcuate plate 139 which is secured on outer face 134. Thus guard 136 is permitted limited movement, and

serves as a stop to prevent the retraction of end 130 into the interior of recess 118. Guard 136 also prevents moisture from passing through slot 132 into the interior of the device.

A projection 138 may be formed on wall 112. This projection may have an opening 140. In a manner similar to screw 92, a screw 142 may be assembled on projection 138 by means of a ball-and-socket connection. An ear 144 may be affixed to or form a part of guard 136, and may have a ball-and-socket-supported threaded member 145 to permit facility in bringing screw 142 into engagement with a threaded opening 147 in member 145.

Glass shade 100 may have an opening 148 having a flange 150. A groove 152 may be provided in flange 150 for engagement by band 120. Band 120, on manipulation of ear 144, will be contracted into groove 152 in the manner hereinbefore described. If it is desired, members similar to straps 56 may be provided. However, the engagement of the band through tangential slot 132 has been found sufficient to retain the band in arcuate formation.

As ear 144 approaches projection 138, or as handle 68 approaches ear 80, the angular extent of the band increases while the effective area of the respective openings are decreased, yet the effective length of the bands remains the same. Also it is to be noted that there is no point contact between the band and the shade or the socket, as the case may be, so that the flat contacting surfaces of band and groove result in transmission of force in such manner that no direct breaking stress is produced either in socket or in shade.

Many other changes could be effected in the particular apparatus designed, and in the methods of operation and use set forth, and in specific details thereof, without substantially departing from the invention intended to be defined in the claims, the specific description being merely of exemplifying embodiments in accordance with the statutes.

What is claimed as new and useful is:

5. Means for supporting a lamp shade in position in relation to an electric-light-bulb-retaining socket, the means including an annular member, the annular member carrying a flexible band of material and positioning the band between the socket and the shade, the ends of the band extending past each other to form a complete loop within the annular member, immediately juxtaposed portions of the looped band being interlocked so that they cannot move apart but can move relatively to each other, and means for moving the ends of the band relatively to each other to adjust the effective area encompassed by the looped band.
10. Means for supporting a lamp shade in position in relation to an electric-light-bulb-retaining socket, the means including an annular member, a flexible band of material housed within the annular member, the annular member positioning the band between the socket and the shade, the ends of the band extending past each other to form a complete loop within the annular member, immediately juxtaposed portions of the looped band being interlocked so that they cannot move apart but can move relatively to each other, and means for moving the ends of the band relatively to each other to adjust the effective area encompassed by the looped band.
15. Means for supporting a lamp shade in position in relation to an electric-light-bulb-retaining socket, the means including an annular member, the annular member carrying a flexible band of material and positioning the band between the socket and the shade, the ends of the band extending past each other to form a complete loop within the annular member, immediately juxtaposed portions of the looped band being interlocked so that they cannot move apart but can move relatively to each other, and means for moving the ends of the band relatively to each other to adjust the effective area encompassed by the looped band.
20. Means for supporting a lamp shade in position in relation to an electric-light-bulb-retaining socket, the means including an annular member, the annular member carrying a flexible band of material and positioning the band between the socket and the shade, the ends of the band extending past each other to form a complete loop within the annular member, immediately juxtaposed portions of the looped band being interlocked so that they cannot move apart but can move relatively to each other, and means for moving the ends of the band relatively to each other to adjust the effective area encompassed by the looped band.
25. Means for supporting a lamp shade in position in relation to an electric-light-bulb-retaining socket, the means including an annular member, the annular member carrying a flexible band of material and positioning the band between the socket and the shade, a portion of the band being formed with an opening, another portion of the band being formed with a reduced portion, the reduced portion and the opening cooperating so that the ends of the band extend past each other to form a complete loop within the annular member, and means for moving the ends of the band relatively to each other to adjust the effective area encompassed by the looped band.
30. Means for supporting a lamp shade in position in relation to an electric-light-bulb-retaining socket, the means including an annular member, the annular member carrying a flexible band of material and positioning the band between the socket and the shade, a portion of the band being formed with an opening, another portion of the band being formed with a reduced portion, the reduced portion and the opening cooperating so that the ends of the band extend past each other to form a complete loop within the annular member, and means for moving the ends of the band relatively to each other to adjust the effective area encompassed by the looped band.
35. Means for supporting a lamp shade in position in relation to an electric-light-bulb-retaining socket, the means including an annular member, the annular member carrying a flexible band of material and positioning the band between the socket and the shade, a portion of the band being formed with an opening, another portion of the band being formed with a reduced portion, the reduced portion and the opening cooperating so that the ends of the band extend past each other to form a complete loop within the annular member, and means for moving the ends of the band relatively to each other to adjust the effective area encompassed by the looped band.
40. Means for supporting a lamp shade in position in relation to an electric-light-bulb-retaining socket, the means including an annular member, the annular member carrying a flexible band of material and positioning the band between the socket and the shade, a portion of the band being formed with an opening, another portion of the band being formed with a reduced portion, the reduced portion and the opening cooperating so that the ends of the band extend past each other to form a complete loop within the annular member, and means for moving the ends of the band relatively to each other to adjust the effective area encompassed by the looped band.

SOUREN R. KAZANJIAN.
